APPARATUS FOR CASTING.
APPLICATION FILED MAY 1, 1913.

Patented July 28, 1914.

2 SHEETS—SHEET 2.

The image contains four technical drawings of a device, likely a projector, labeled Fig. 4, Fig. 5, Fig. 6, and Fig. 7. Fig. 4 is a side view showing a base 44, a housing 45, and a lens 46. Fig. 5 is a top-down view showing internal components including a base 27, a housing 13, and various numbered parts (10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48). Fig. 6 is another top-down view similar to Fig. 5 but with different component labeling (10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48). Fig. 7 is a front view showing a base 10, a housing 13, and a lens 16. The drawings illustrate the internal and external structure of the device, including its base, housing, lens, and various internal parts and supports.

UNITED STATES PATENT OFFICE.

CLIFTON D. PETTIS, OF CHICAGO, ILLINOIS.

APPARATUS FOR CASTING.

1,104,926.

Specification of Letters Patent.

Patented July 28, 1914.

Application filed May 1, 1913. Serial No. 764,825.

To all whom it may concern:

Be it known that I, CLIFTON D. PETTIS, a citizen of the United States, residing at Chicago, county of Cook, and State of Illinois, have invented certain new and useful Improvements in Apparatus for Casting, of which I do declare the following to be a full and exact description, reference being had to the accompanying drawings, forming a part 10 of this specification.

The present invention has for its object, more particularly, to provide an improved apparatus for the casting of railway brake shoes, although it will be understood that 15 the invention, in part at least, is applicable to other uses.

Figure 1 is a view in side elevation of an apparatus embodying my invention. Fig. 2 is an inverted plan view of the upper portion 20 of the apparatus. Fig. 3 is a plan view of the lower portion of the apparatus. Fig. 4 is a perspective view of the pan-shaped shell or back for reinforcing brake shoes. Fig. 5 is a view in cross-section on line 5—5 25 of Fig. 1. Fig. 6 is a view in cross-section on line 6—6 of Fig. 1. Fig. 7 is a view similar to Fig. 6 illustrating a modification.

In the preferred embodiment of my invention as adapted for the manufacture of 30 brake shoes, the lower portion of my improved apparatus comprises a chambered metal body 10, the interior of which will be filled with fire clay or like refractory material 11 that will not tend to chill the 35 metal cast therein. In the curved top of the lower portion 10 is formed a long cut-away space 12 corresponding in size and shape to the outline of the body portion of the brake shoe and beneath this cutaway 40 space 12 a corresponding recess 13 is formed in the upper portion of the refractory material 11.

The upper part of my improved casting apparatus consists preferably of two metal 45 sections 15 and 16. Each of these sections is provided adjacent its ends with lugs 18 that will be pivotally connected with corresponding lugs 19 that project laterally from the lower portion of the apparatus. Preferably the pivotal connections between the lugs 18 of the sections 15 and 16 and the lugs 19 is effected by means of pivot-rods 20 that pass through suitable holes formed in the lugs. Each of the pivoted sections 15 and

16 is formed upon its under side with a shallow recess 22 corresponding in length to the length of the body of the brake shoe and corresponding in width to one-half of the width of such shoe, and each of the sections 15 and 16 is formed centrally with a deeper 60 transverse cavity 23 to receive or form the corresponding half of the center lug of the shoe, and is formed at its end with a transverse cavity 24 to receive or form half of the end lug of the shoe. It will be understood, of course, that the precise shape of the cavities 23 and 24 will depend upon the character and shape of the center and end lugs of the shoe.

In each of the sections 15 and 16 are 70 formed halves of the pouring holes 26 through which will be poured the metal or other material that is to constitute the body of the shoe. When the sections 15 and 16 are in the closed position shown in Figs. 1 75 and 5 of the drawings, these sections will be at a distance above or spaced from the top of the lower portion 10 of the apparatus, with the cavities of the sections 15 and 16 immediately above the space 12 and 80 cavity 13 of the lower portion 10. As the contact of the abutting faces of the sections 15 and 16 arrests any further downward movement of the sections, a simple means 85 is thus provided for holding the upper sections when in closed position at a distance above the lower section of the mold. The distance between the sections 15 and 16 when in closed position, and the portion 10, will determine the height or vertical thickness 90 of the brake shoe to be cast; and in order that such dimensions of the brake shoes may be conveniently varied to meet the requirements of different railroads, I provide for relative adjustment of the sections and lower 95 portion 10, preferably as hereinafter more fully set forth.

As shown, the pivot lugs 19 are formed integral with the side bars 27 that are adjustably attached to the lower portion 10 of the 100 apparatus. This adjustable attachment of the parts 27 to the lower portion 10 may be effected by means of through-bolts 28 that pass through the body 10 and through the bars 27, the ends of the bolts 28 being provided with threaded nuts 29. It will be observed that the holes 30 in the bars 27 through which the bolts 28 pass are in hori-

zontal alinement, while the holes 32 through the lower portion 10 are arranged at different distances from the bottom of the lower portion 10. Hence, it will be seen that when the bolts 28 are passed through the lowermost holes 32 in the portion 10, said portion 10 will be held closer to the sections 15 and 16 than when the bolts 28 are in the holes 32 farther from the bottom of the portion 10. Thus, for example, if a comparatively thin brake shoe is to be formed (say a shoe 1½ inches thick), the bolts 28 will be passed through the end holes 30 and 32, whereas if a very thick brake-shoe (say a shoe 2 inches thick) is to be formed, the bolts 28 will be passed through the innermost holes 30 and 32. While I have thus provided one efficient means for effecting the relative adjustment of the lower and upper portions of the apparatus, it is obvious that such relative adjustment can be secured in a great variety of ways without departing from the scope of the invention.

My present invention is more especially designed for the manufacture of that form of reinforced brake shoes (an example of which is shown in application for Letters Patent filed by me in the United States Patent Office August 3, 1912, Serial No. 713,177) in which the cast body of the shoe is reinforced upon its back, sides and ends with a pan-shaped shell or back in the casting operation.

In Fig. 4 of the drawings, I have shown one form of pan-shaped back or shell adapted to be used in the practice of my present invention, and in Figs. 5 and 6 I have shown this back or shell as set in the mold in readiness to receive the material, such as molten metal, of which the body of the shoe is formed. The pan shaped back or shell is shown as provided with holes 41 adapted to come opposite the pouring holes of sections 15 and 16 and it is also provided, at its center and adjacent its ends, with openings 42 and 43 through which the cast metal will flow into the cavities 23 and 24 of the sections 15 and 16 to form the center and end lugs, respectively, of the shoe, if these lugs are to be formed in whole or part of the cast metal or other material which forms the body of the shoe. If the center and end lugs are formed entirely of ductile metal or if ductile metal parts are used to reinforce these lugs, such ductile metal pieces will be placed in the cavities 23 and 24 of the sections 15 and 16 before the casting operation. In the particular construction shown, the end lugs are formed in part of portions 44 of the pan shaped back or shell, and partly of cast metal or the like which fills the portions 44 and which flows through the openings 43 into the cavities 24 of the sections 15 and 16. In the construction shown, the center lug is reinforced by a staple-like piece

45 of ductile metal, the ends of which are interlocked with the back of the pan shaped shell. This reinforcing strip is held in position by a core 46 inserted within it and above the back of the reinforcing shell, as 70 shown in Fig. 5.

In the form shown in Figs. 4 and 6, the end walls of the shell 40 are provided with downwardly projecting tongues 47 which are adapted to rest in the bottom of the recess or cavity 13 in the lower body portion 10. These tongues thus hold the lower edges of the pan or shell at a distance above the bottom of the cavity 13 so that, when the material is poured into the shell, it will fill 80 that part of the cavity 13 below the lower edges of the shell 40. While it is not essential, some means is preferably provided for thus holding the shell 40 in position with its lower edges above the bottom of the 85 cavity 13, so that the shell or back of the shoe shall terminate at a considerable distance from its wearing face. In the modification shown in Fig. 7, the refractory material 11 projects inwardly to a slight extent beyond the edges of the opening 12 in the top of the lower body portion 10, so that a shoulder 48 is formed about the cavity 13. This shoulder is arranged above the bottom of the cavity and the edges of the pan 95 shaped back or shell rest thereon during the casting operation.

When the pan shaped shell or back 40 is placed in position in readiness for the casting operation, as shown in Figs. 5 and 6 of 100 the drawings, it will be seen that the side and end walls of the back or shell 40 span the space between the lower section 10 and the upper sections 15 and 16 of the apparatus, and the shell thus forms, in effect, a 105 part of the mold for the casting operation. Preferably, the sections 15 and 16 are quite thick and heavy, so that they will securely hold the back in position. When the material, such as molten metal, is poured through 110 the holes in the sections 15 and 16 and through the back of the shell, it will fill the latter and the cavity 13 of the lower portion 10 and will also fill the center and end lug cavities 23 and 24 of the sections 15 and 16, 115 and the body of the shoe will be securely united to the shell in the casting operation. When metal is used, the shell, in effect, forms an integral part of the body of the shoe and provides, as it were, a tough skin 120 or armour for the back and side walls thereof. The shell is preferably formed of very thin ductile metal, which, I have found in practice, may be employed without danger of the molten metal burning through 125 the walls thereof. By using such a pan shaped shell in the casting operation, the same set of parts or mold sections may be employed for shoes of different thickness as the side and end walls of the shell will span 130

the open space between the upper and lower portions of the apparatus and will permit such parts to be separated more or less to enable shoes of different thicknesses to be cast. The apparatus also obviates the necessity of employing sand molds, and at the same time, obviates the disadvantageous chilling of the body of the shoe occasioned by the use of metal molds. In the construction shown, the face of the shoe is formed by the cavity 13 in the refractory material 11 which, of course, does not act to chill the metal. The shell, as stated, is formed of very thin ductile metal which heats up rapidly when the molten metal is poured into it and, inasmuch as the side walls of the shell are exposed between the lower section 10 and the upper sections 15 and 16, such side walls will have little or no cooling action upon the body of the shoe. It should be noted, that the shell is securely held in position by the walls of the opening 12 in the lower section 10 and within the cavity 22 of the upper sections 15 and 16. The shells can be formed inexpensively by stamping operations and can be quickly placed within the apparatus set forth for the casting operation. By forming the upper portion of the apparatus of two separate sections, with the pouring openings 26 extending between the meeting faces thereof, the sections can be quickly opened to release the shoe and the gates or portions of cast metal formed within the pouring openings.

35 It will be understood that the details of construction set forth may be varied without departing from the spirit of the invention and that features thereof may be employed without its adoption as an entirety. 40 The terms "upper" and "lower" as herein used are not to be understood as terms of limitation, since the relative position of the mold sections may be changed without departing from the spirit of the invention.

Having thus described my invention, what I claim as new and desire to secure by Letters Patent, is:—

1. A casting apparatus comprising upper and lower sections provided with means for holding a shell in position between said sections and constructed to form a space outside the walls of said shell when the sections are in closed position to expose the shell to the cooling action of the air, one of said sections being provided with a pouring hole whereby metal may be admitted to the interior of said shell.

2. A casting apparatus comprising upper and lower sections adapted to hold a shell conforming in outline to the shape of a brake shoe in position between said sections and constructed to form a space outside the walls of said shell when the sections are in closed position to expose the shell to the

cooling action of the air, said lower section being provided in its upper part with a mold cavity corresponding in outline to the face of the brake shoe and adapted to coincide with the walls of said shell, and means independent of the shell for adjustably holding said sections at different distances apart. 70

3. A casting apparatus comprising a lower portion provided in its upper part with a mold cavity, and an upper portion formed of movable sections, said upper sections when in closed position being held at a distance above the cavity of the lower section to form a wide space above said cavity. 75

4. A casting apparatus comprising a lower portion provided in its upper part with a mold cavity and an upper portion formed of sections pivotally connected with the lower portion, said upper sections being formed with downwardly-facing cavities 85 and being held when in closed position at a distance above said lower portion to form a space around the casting made by the mold. 80

5. A casting apparatus comprising upper and lower portions provided with means for holding a shell in position between them and constructed to form a space outside the walls of said shell when the portions are in closed position to expose the shell to the cooling action of the air, one of said portions being chambered and having a filling of refractory material provided in its upper face with a mold cavity to come opposite said shell. 90

6. A casting apparatus comprising upper 100 and lower portions provided with means for holding a shell conforming in outline to a brake shoe in position between them and constructed to form a space outside the walls of said shell when the portions are in closed position to expose the shell to the cooling action of the air, said upper portion being formed of sections pivotally and adjustably connected to the lower portion whereby the space outside the walls of said shell may be 110 varied when said upper portions are in closed position. 105

7. A casting apparatus for forming brake shoes comprising a chambered lower portion having a top provided with a recess in its upper part, a filling of refractory material within said lower portion provided with a cavity corresponding with and immediately beneath said recess in said top, and an upper portion to hold a pan or shell, said upper portion being provided with a longitudinal cavity above the recess of said lower portion and with cavities or spaces for the center and end lugs of the shoe. 115

8. A casting apparatus comprising a 125 lower portion provided in its upper part with a mold cavity, lugs projecting laterally from said lower portion, an upper portion formed with sections provided with laterally projecting lugs pivotally connected 130

to the side lugs of the lower portion, and means for vertically adjusting said lower lugs upon said lower portion.

9. A casting apparatus comprising a lower portion, bars extending along the sides of said lower portion and provided with pivot lugs projecting laterally therefrom, said bars being adjustable upon said

lower portion, and an upper portion formed of sections provided with laterally projecting lugs pivoted to the said first mentioned lugs.
